UNITED STATES PATENT OFFICE.

ROBERT A. McCARTY, OF DETROIT, MICHIGAN, ASSIGNOR OF ONE-HALF TO
GEORGE MAITLAND, OF SAME PLACE.

STORE-SERVICE APPARATUS.

SPECIFICATION forming part of Letters Patent No. 325,618, dated September 1, 1885.

Application filed April 11, 1885. (No model.)

To all whom it may concern:

Be it known that I, ROBERT A. McCARTY, of Detroit, in the county of Wayne and State of Michigan, have invented a certain new and useful Improvement in Store-Service Apparatus, of which the following is a specification.

My invention relates to the system of rapid store-service for cash or cash and parcels, wherein the carriers travel upon ways formed of lines of stretched wires, and are impelled by projecting devices located at the ends of the lines, such system being broadly covered by an application for Letters Patent already filed by me, Serial No. 122,626.

The present invention consists in the arrangement and combination of apparatus for a general store system, comprising a number of lines, and providing for service between the cashier and salesmen at several points in the store, whereby simplicity and cheapness in construction will be attained; in the construction or arrangement of the projecting devices to form buffers for receiving the carriers when shot from the opposite ends of the ways; in the manner of supporting the projecting devices, and in certain details of construction, including an efficient form of catch for locking the carriers at the ends of ways, a convenient and efficient carrier and removable receptacle depending therefrom, and in other details, all as more fully hereinafter explained.

In the accompanying drawings, forming a part hereof, Figure 1 is a side elevation of the apparatus, showing one line completed; Fig. 2, a perspective view from beneath of the cashier's apparatus partially developed; Fig. 3, a plan of the same; Fig. 4, a perspective view of the salesman's apparatus; Fig. 5, a perspective view of the traveling carrier with receptacle removed therefrom; Fig. 6, a similar view of receptacle; Fig. 7, a bottom view of the locking-catch, and Fig. 8 a central longitudinal section of such catch.

Like letters denote corresponding parts in all the figures.

In my store service system there is provided a line-wire, A, for each station, such line-wire extending from the cashier's desk B to a point in the store—say C—between which and the cashier's desk it is desired to establish com-

munication. This line is a stretched horizontal wire, and at each end there is provided a spring-projecting device for shooting the carrier, which travels thereon, to the other end of the wire, as well as receiving and locking devices which stop the carrier and lock it in position until projected again to the other end of the line. At the cashier's desk the several service-lines meet.

For simplicity and cheapness in the construction, as well as in the supporting of the projecting devices, such projecting devices are combined at the cashier's desk in a common frame, D. This is shown more particularly in Figs. 2 and 3, and consists, essentially, of the two curved bars *a b*, arranged one in front of the other, substantially in the same horizontal plane, and supporting, respectively, the catches E for locking the carriers, and the forks F, which hold the bights of the propelling and buffer cords upon the line-wires, and also of a third curved bar, *c*, which is located above bar *a*, and carries the sheaves *d* for the operating-cords. These bars are connected together by bars and braces, as shown, and are supported from the wall or ceiling, or both, or from the desk, in any suitable way. The bars *a b c* have a curve which is more or less of a complete circle, according to the directions taken by the most divergent lines.

All points in the store may communicate with one cashier's desk, or two or more of such desks may be used, each with its system of diverging service-lines.

The catches, operating-cords, and other devices used upon the cashier's apparatus are the same as the parts employed upon the salesman's apparatus, in connection with which they will be described.

The salesman's apparatus has a vertical supporting-pipe, G, which carries the operating parts. This pipe is preferably hung from the ceiling by a connecting-pipe, *e*, and a ceiling-flange, *f*, the pipe *e* being of sufficient length to give the apparatus the desired elevation. The line-wire A passes through a hole, *g*, in pipe G, near its lower end, and then extends to the wall, or upwardly to the ceiling, where it is secured and properly stretched. In hole *g* is a nipple, *g'*, provided with screw

g^2 for clamping pipe G to the line-wire. This stays the apparatus in the direction of the line-wire. Laterally the pipe G is braced by an arm, h, which extends to shelving, to the wall, or to any near stationary object, to which it is secured. By staying the pipe G in this way in both directions it can be hung from the ceiling. The frame D of the cashier's apparatus may also be stayed in the same way.

10 Above line-wire A there projects from pipe G a horizontal arm, H, extending along over the wire, and having a fork, F, at its end, the arms of which bend down nearly to the plane of the wire. The ends of the fork F carry 15 sheaves, and over these passes the cord i, the bight of which rests upon the wire. Blocks k, preferably of soft rubber, are placed upon the cord below the fork, and prevent the bight from pulling up to the sheaves, at the same time that they keep the bight from 20 twisting from a proper position upon the line-wire. The arm H is braced from the pipe G by a rod, l. The cord i is secured at its upper end to a spring, I, which may be a piece 25 of rubber tubing or a metal spiral, and from the other end of this spring two cords or wires, m n, run over sheaves in the head o of pipe G, and then hang downwardly in the rear of such pipe.

30 To the lower end of pipe G is secured the catch E. This is composed of an arm, E', which is clamped to the lower end of pipe G, and projects outwardly in the same direction as arm H, but below instead of above the line-wire. This is forked at its outer end, and has pivoted to such forked end a bottom plate, E², which extends back of pipe G, and has in its rear end two holes, through which the operating-cords m n pass. This plate E² is held up 35 against arm E' by a spring, p. It carries a latch, K, which projects through an opening in arm E'. This latch is pivoted upon plate E², and is thrown up by a light quick-acting spring, p'. The carrier, in engaging with the catch, depresses only the latch K, requiring 40 but little force to overcome the spring p', while to release the carrier the plate E² is drawn 45 downwardly against the greater tension of spring p. This double or compound catch is 50 a highly-efficient device. If the latch K were not independently pivoted upon plate E², it would be necessary for the carrier to overcome the tension of spring p and force the plate itself down in order to engage the catch.

55 The cords m n, which terminate in rings or knobs within convenient reach, are provided above the catch-plate E² with adjustable stops q' q'', which may be balls held upon the cords by set-screws. These are adjusted upon the 60 cords to the required points for giving the spring I the proper tension, and their purpose is to draw down the catch-plate E² and release the carrier. The stop q' upon the cord n of each apparatus is adjusted to a higher 65 point than stop q of cord m, so that by pulling upon cord n the spring will be given greater tension before the carrier is released,

and the carrier can be propelled with a greater load than if the cord m is used to operate the apparatus.

70 When the carrier is lightly loaded, the cord m will be used to operate the apparatus, and when the carrier is heavily loaded the cord n will be employed for this purpose. Since the stops q' q'' can be readily adjusted, the same size spring can be used for all the machines, although the lines are of different lengths; but heavier springs might be used in machines for the longest lines. The result of depending upon the adjustment of the stops q' q'' is 75 that such stops will be at different points upon the several machines at the cashier's desk, as well as upon those at the outer ends of the lines.

80 The carrier that I prefer to employ is a narrow plate, L, upon which are mounted two grooved wheels, L' L'', of hard rubber or other suitable material. These wheels ride upon the wire A, while the plate L hangs beneath the wire. The plate L is provided with set-screws r, projecting upwardly through it, one near each wheel. These screws are adjusted to limit the jumping movement of the carrier on the wire, so as to prevent its displacement thereon. Near each end the plate L is formed 85 into upwardly-projecting hooks M, and at each end the plate terminates in a head, N, forming a downwardly-projecting hook, which head is capped by a buffer, s, of soft rubber.

85 From the center of plate L is hung by rods t a horizontal ring, O, provided with notches u on its inner edge.

90 The receptacle P is a cylindrical box with open top, and has a shoulder, v, and pins w above the shoulder. The box P is attached 95 to the carrier by pushing it into the ring, so that pins w will pass through notches u, and then turning it to lock the box to the ring.

95 A box-cover, Q, is hung from the bottom of plate L by a spiral spring, x, which presses 100 the cover down upon the box, closing such box and holding it firmly in position in the ring.

105 When a carrier is projected over a wire, the hooks M at the forward end of the carrier catch the bight of the spring-cord at the other end of the line, and pulling back such bight draw down upon the propelling-spring; hence it will be seen that the propelling-spring can also be used as a buffer-spring. To 110 accomplish that, I secure to the cord m or n of each machine, below the catch-plate E², a stop, y, which may be a metal ball adjustably held by a screw upon such cord. This stop is adjusted to the proper point with relation 115 to the momentum of the carrier, so that it will strike the plate E² and permit spring I to be strained by the moving carrier as its hook-head N is passing over latch K. This 120 adjustment will be such that the carrier will engage the latch with certainty, but will then be stopped by the spring I. Should the carrier go farther and its head strike the pipe G, it can only do so with slight force, and the 125 130 135

buffers s will suffice to prevent injury to parts or the production of a disagreeable noise.

The construction of the projecting device, *per se*, except in the particulars hereinafter 5 pointed out by the claims, is covered by an application for Letters Patent already filed by me, (Serial No. 130,126,) and hence is not claimed herein.

What I claim is—

10 1. A store-service apparatus wherein are combined two or more service-lines diverging from a common point, each running to a single station, carriers traveling upon said lines, and motors for projecting said carriers over said lines, substantially as set forth.

2. A store-service apparatus wherein are combined two or more horizontal service-lines diverging from a common point, each running to a single station, carriers traveling upon 20 said lines, and stationary motors located at both ends of the lines, for projecting the carriers back and forth over said horizontal lines, substantially as set forth.

3. A store-service apparatus wherein are combined two or more lines of varying lengths diverging from a common point, each running to a single station, carriers traveling upon 25 said lines, and adjustable motors for projecting the carriers over said lines, such motors being adjusted with relation to the length of two or more lines, substantially as set forth.

4. In store-service apparatus, the combination, with the cashier's desk or other common point of delivery, of two or more service-lines 30 diverging therefrom, two or more motors for projecting carriers over said lines, and a common frame in which said motors are mounted, substantially as set forth.

5. In store-service apparatus, the combination, with two or more motors mounted in a common frame at a central point, horizontal lines diverging therefrom to separate stations, and separate motors at such stations, all said 40 motors being adapted to project carriers over such lines, substantially as set forth.

6. In store-service apparatus, the combination, with a line, of a spring-motor located at one end thereof in position to receive and stop as well as to project a carrier traveling 45 upon said line, whereby the motor-spring will act also as a buffer, substantially as set forth.

7. In store-service apparatus, the combination, with a line and a carrier traveling thereon, of a spring-motor located at each end thereof in position to receive and stop as well 50 as to project the carrier, substantially as set forth.

8. In store-service apparatus, the combination, with a line and a carrier traveling thereon, of a spring-motor located at one end of 55 the line in position to receive and stop the carrier as well as to project it over the line, a catch with which the carrier engages by its own momentum, and an adjustment to the 60 motor, whereby the motor-spring can be

brought into action as a buffer at the proper point to stop the carrier after it has engaged with the catch, substantially as set forth.

9. In store-service apparatus, the combination, with a motor for projecting the carrier, of 70 adjustable operating-stops arranged to cause the motor to act with different force to propel the carrier when lightly or heavily loaded, substantially as set forth.

10. In store-service apparatus, the combination, with a spring-motor for projecting a carrier, of a catch for holding the carrier against tension of the spring, two or more 75 cords for straining the spring, and adjustable stops on said cords for releasing the carrier 80 at different degrees of tension of the spring, substantially as set forth.

11. In store-service apparatus, the combination, with the motor for projecting the carrier, of a catch for holding the carrier 85 carried by a plate pivoted forward of the catch, and extending in rear of catch for engagement with operating-stops, substantially as set forth.

12. In store-service apparatus, the combination, with the motor and carrier, of a compound catch having a latch movable independently of a movable plate upon which it is mounted, substantially as set forth.

13. In store-service apparatus, the combination, with the motor and carrier, of a pivoted spring catch-plate having a spring-latch pivoted thereon and capable of independent movement, substantially as set forth.

14. In store-service apparatus, the combination, with the stretched wire, of the spring-motor hung from ceiling and clamped to such wire, and the lateral stay, substantially as set forth.

15. In store-service apparatus, the combination, with a stretched wire way, of a wheeled carrier traveling thereon, and adjustable screws limiting the vertical movement of the carrier on the wire, substantially as set forth.

16. In store-service apparatus, the combination, with a stretched wire way, of a wheeled carrier traveling thereon and a receptacle suspended beneath the carrier and removably held thereto by a depending ring, substantially as set forth.

17. In store-service apparatus, the combination, with a stretched wire way, of a wheeled carrier traveling thereon, a receptacle removably locked to such carrier, and a spring-cover for the receptacle held permanently by the carrier, substantially as set forth.

This specification signed and witnessed this 26th day of March, 1885.

ROBERT A. McCARTY.
